UNITED STATES PATENT OFFICE

92,001

DESIGN FOR A CIGARETTE SERVER

Alfred P. Hirschfeld, Meriden, Conn., and William O. Tuckerman, Hyde Park, Mass., assignors to The Bradley & Hubbard Mfg. Co., Meriden, Conn.

Application November 8, 1933, Serial No. 49,676

Term of patent 7 years

To all whom it may concern:

Be it known that we, ALFRED P. HIRSCHFELD and WILLIAM O. TUCKERMAN, citizens of the United States, residing respectively, at Meriden, in the county of New Haven and State of Connecticut, and Hyde Park, in the county of Suffolk and State of Massachusetts, have invented a new, original, and ornamental Design for Cigarette Servers, of which the following is a specification, reference being had to the accompanying drawing, forming part thereof.

We claim:

The ornamental design for a cigarette server substantially as shown.

ALFRED P. HIRSCHFELD.

WILLIAM O. TUCKERMAN.
